UNITED STATES PATENT OFFICE.

GEORGE W. BARTLETT, OF SPOKANE, WASHINGTON.

BURNER.

1,159,314.

Specification of Letters Patent.

Patented Nov. 2, 1915.

Application filed November 30, 1914. Serial No. 874,873.

To all whom it may concern:

Be it known that I, GEORGE W. BARTLETT, a citizen of the United States, residing at Spokane, in the county of Spokane and State of Washington, have invented certain new and useful Improvements in Burners, of which the following is a specification, reference being had to the accompanying drawings.

10 This invention relates to certain improvements in burners and has relation more particularly to a device of this general character, wherein a liquid fuel is atomized and delivered in the form of spray through the medium of an expansible fluid; and the object of the invention is to provide a device of this type having novel and improved means whereby the liquid fuel and the expansive fluid are adapted to coact in such a manner as to result in a maximum of efficiency.

15 The invention consists in the details of construction and in the combination and arrangement of the several parts of my improved burner whereby certain important advantages are attained and the device is rendered simpler, less expensive and otherwise more convenient and advantageous for use, all as will be hereinafter more fully set forth.

20 The novel features of the invention will be carefully defined in the appended claim.

In order that my invention may be the better understood, I will now proceed to describe the same with reference to the accompanying drawings, wherein—

25 Figure 1 is a longitudinal sectional view taken through a burner constructed in accordance with an embodiment of my invention, the delivery tube positioned therein being shown partly in elevation; Fig. 2 is a sectional view taken substantially on the line 2—2 of Fig. 1; Fig. 3 is an enlarged rear elevational view of the casting comprised in the invention as herein disclosed; Fig. 4 is a front elevational view of the casting; and Fig. 5 is a fragmentary longitudinal section taken through the inner end of the casting and illustrating in detail certain features of the invention as herein embodied.

30 As disclosed in the accompanying drawings, 1 denotes an elongated cylindrical conduit of predetermined dimensions having engaged with one extremity a casting C substantially rectangular in form and having

one extremity provided with the integrally connected annular flange 2, the inner wall 3 whereof being threaded in order that a convenient connection may be had with an extremity of the conduit 1. The casting C is hollow and is divided into the substantially rectangular compartments *a* and *b* through the medium of the septum or partition 4. The inner end wall 5 of the compartment *a* has produced therein an opening 6 in communication with the recess or pocket 7 produced in said wall 5 and the adjacent end of the septum 4 and in which is adapted to be engaged the extremity of a fuel delivery pipe 8 which extends through the conduit 1 and is adapted to be connected with a suitable source of fuel supply, and it is to be observed that the compartment *a* is of a depth materially less than the diameter of the bore of the pipe 8. As is believed to be self-evident, the fuel delivery pipe 8 is of less transverse diameter than that of the conduit 1 whereby a space 9 is afforded, for a purpose which will hereinafter be more particularly referred to.

35 The opposite extremity of the conduit 1 has engaged therewith a T coupling 10 through the outer extremity of which is directed the delivery pipe 8, the inner extremity whereof being threaded, as herein disclosed, within the recess 7, hereinbefore referred to. The outer extremity of the coupling 10 has its periphery threaded, as indicated at 11, and which is engaged by the packing nut 12 through which the delivery pipe 8 projects and whereby a hermetical connection is assured.

40 Operatively connected with the lateral member 14 of the coupling 10 is a conduit 15 leading from a suitable source of expansive fluid, such as steam or air, which travels through the conduit 1 within the space 9 and through the compartment *b* within the casting C and through the restricted mouth or slot 18 produced in the outer wall of the compartment *b* and of an extent slightly in excess of the interior transverse diameter of the compartment *b*. It is also to be observed that the forward wall 16 of the compartment *b* is substantially semi-circular in form whereby a maximum of efficiency of the spray of the device may be attained. The outer face of the compartment *a* is open, as indicated at 17, and of substantial rectangular formation and it is to be observed that the opening 6

is materially smaller than the transverse diameter of the recess 7 whereby the operation of the burner is greatly facilitated. It is to be further observed that the discharge end of the compartment *a* is in advance of the discharge end of the compartment *b*, as is clearly shown in Fig. 1 of the drawings.

From the foregoing description, it is thought to be obvious that a burner constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

A device of the character described comprising a hollow casting divided longitudinally into two compartments of substantially rectangular form, the forward face of one compartment being open and the for-

ward wall of the adjacent compartment being semi-circular in form and provided with a slot at its inner face disposed transversely therethrough and in communication with the compartment, said slot being of an extent in excess of the interior transverse diameter of the compartment, an elongated conduit operatively engaged with the inner end of the casting and in communication with the second named compartment, the inner end of the first named compartment being provided with a pocket, a fuel delivery pipe disposed through the conduit and operatively engaged with said pocket and in communication with the first named compartment, said first named compartment being of a depth materially less than the diameter of the bore of the delivery pipe, and means for admitting expansive fluid within the conduit, the discharge end of the first named compartment being in advance of the discharge end of the second compartment.

In testimony whereof I hereunto affix my signature in the presence of two witnesses.

GEORGE W. BARTLETT.
